UNITED STATES PATENT OFFICE

92,576

DESIGN FOR AN OVERALL

Saul Bleier, New York, N. Y.

Application February 23, 1934, Serial No. 50,829

Term of patent 7 years

To all whom it may concern:

Be it known that I, SAUL BLEIER, a citizen of the United States, residing at New York city, in the county of New York, and State of New York, have invented a new, original, and ornamental Design for Overalls, of which the following is a specification, reference being had to the accompanying drawing, forming part thereof.

Fig. 1 is a front view of an overall, showing my new design.

Fig. 2 is a rear view of the same.

I claim:

The ornamental design for an overall as shown. In testimony whereof I have affixed my signature.

SAUL BLEIER.
